ELECTRIC CURRENT RECTIFIER

Oskar Seitz, Baden, Switzerland, assignor to Aktiengesellschaft Brown Boveri & Cie., Baden, Switzerland, a joint-stock company of Switzerland

Application October 29, 1929, Serial No. 403,280
In Germany November 8, 1928

4 Claims. (Cl. 250—27.5)

This invention relates to improvements in electric current rectifiers of the metallic vapor type and, more particularly, to the construction about the inlets through the top plate of such rectifiers 5 adapted to receive the anodes thereof.

Heretofore, it has been considered necessary to separate the operative space about the anodes of an electric power rectifier from the inoperative space as completely as possible by sealing the arc 10 guides against the insulators surrounding the anode conductor. Such sealing or closure, however, requires a complicated construction in order to equalize the action of the heat on the various 15 portions and various materials and the insulator for the anode supply conductor is likewise complicated thereby. It has usually been considered necessary to interpose a packing of heat-resistive material between the anode proper and the lower 20 surface of the insulator for the purpose of obtaining uniform contact between the two portions and of sealing the operative space against the exterior inoperative space. Such packing was necessarily compressed with considerable force between the 25 anode and the insulator so that, due to such pressure the insulator was severely stressed mechanically in addition to the thermal stresses produced by the temperatures encountered within such rectifiers.

It is, accordingly, among the objects of the 30 present invention to provide an anode inlet structure for electric power rectifiers in which a closure of the operative space from the inoperative space of the rectifier will be unnecessary.

Another object of the present invention is to 35 provide an anode inlet structure in which the operative portion about the anode of an electric power rectifier will be indirectly connected with the inoperative portion thereof.

A further object of the invention is to provide 40 for an indirect connection between the operative space about the anodes of a metallic arc rectifier with the inoperative space in such manner that a constant upward flow of metallic fluid is maintained in the operative space and that it will be 45 impossible for condensed metallic fluid, dropping from the upper portions of the connection structure, to contact with the anode or with the enclosure thereabout.

Objects and advantages, other than those above 50 set forth, will be apparent from the following description and the drawing in which,

Figure 1 is a partial cross sectional view of an 55 electric power rectifier showing an embodiment of the improved inlet structure for an anode,

Fig. 2 is a modified form of the embodiment shown in Fig. 1.

Fig. 3 is a further modification of the embodiment shown in Fig. 1.

Fig. 4 is an embodiment, shown partially in section, of an anode inlet for a metallic vapor rectifier in which the enclosure surrounding the anode is insulated from the rectifier structure, and

Fig. 5 is a partial cross-sectional view similar to those previously described, but showing a modified form of the embodiment shown in Fig. 4.

Referring more particularly to the drawing by characters of reference, the reference numeral 6 indicates a portion of the usual top or cover member for an electric power rectifier of the metallic 15 vapor type. The top portion 6 is usually pierced by a plurality of apertures through which anodes 7 are arranged to extend. The anodes 7 are retained in a flanged closure member 8 which is supported in insulated relation from the top 6 by 20 an insulating member 9. The joints between the closure member 8 and the insulating member 9 and between the insulating member 9 and the top 6 are sealed by sealing rings 10, 11 which may be of 25 any suitable construction but are preferably formed of heat-resistive material.

Each of the anodes 7 is enclosed by an arc guide 13. In the embodiment shown in Fig. 1, the arc guide 13 is maintained in position and connected 30 with the top plate 6 by means of an intermediate member 16 in the form of a flanged cylinder having a substantially conical inwardly extending flange 17. The connection member 16 is also provided with a plurality of apertures 18 through the 35 circumferential portion thereof for a purpose which will appear hereinafter. A shield or deflecting member having a sleeve portion 19 is fitted about the upper portion of the anode in contact with the closure member 8, the deflector member being at the bottom portion thereof in the form of an outwardly extending cone 20 having its truncated apex portion connected with the sleeve 19. During operation of the rectifier, a continuous 40 current of metallic fluid flows through the arc guide 13 in an upwardly direction and discharges 45 into the inoperative spaces of the rectifier through apertures 18. Any of the metallic vapor condensed in the upper portions of the structure will drop on the conical flange 20 and the conical flange 17 and will be discharged through the 50 apertures 18 from which the condensed material will return to its sources.

The embodiment shown in Fig. 2 is similar to that above described with the exception that the 55 connection member 16 is formed with a plurality

of inwardly extending conical flanges **17** arranged one above the other and a plurality of discharge apertures or ports **18**. The sleeve portion **19** likewise differs from that above described relative to Fig. 1 in that a plurality of conical flanges **20** are provided thereon. The several conical flanges **17** of the connection member and the several conical flanges **20** are arranged in an interleaved relation so that a type of labyrinth gland is formed which entirely precludes the possibility of condensed metallic vapor falling or dropping upon the anode **7** or upon the interior surfaces of the arc guide **13**.

Fig. 3 shows an embodiment similar to that shown in Fig. 1, with the difference, however, that the sleeve **19** is arranged to enclose an annular space about the upper portion of the anode itself and the discharge ports **18** are each provided with a discharge spout **21** for the purpose of conducting the condensed metallic material farther beyond the exterior surface of the arc guide than was possible in the embodiments previously described, thereby safe-guarding against the contacting of condensed metallic material with the exterior surfaces of the arc guides.

It may be desirable to form the member intermediate the arc guide **13** and the top **6** of insulating material rather than of conductive material, in which case the structure will assume the form shown in Fig. 4. The substitution of an insulating shield for the metallic shield **19**, **20** may also be desirable, in which case the insulating shield is formed as an insulating sleeve **22**, having an outwardly extending conical flange **23** arranged above the inwardly extending flange **17a** of the connection member. The connection member may likewise be provided with a conical flange **24** formed below ports **18a** therethrough, exteriorly of the connection member, for the purpose of discharging the metallic condensate collected on the flange **17a** at a point away from the exterior surface of the arc guides, to prevent the formation of so-called cathode spots thereon which would permit back-firing in the rectifier.

Although but a few embodiments of this invention have been illustrated and described, it will be understood that various other embodiments are possible and that various changes may be made without departing from the spirit of the invention or the scope of the appended claims.

The invention claimed is:

1. In metallic vapor current-rectifying apparatus, an anode, a structure disposed about said

anode for receiving the vapor particles and permitting free flow of the same about and in contacting relation with said anode, and means disposed within said structure and above said anode for receiving the vapor particles after the same have passed beyond said anode, said means being shaped and disposed to conduct the received vapor and any condensate thereof laterally outwardly from said anode and to discharge such vapor and condensate exteriorly of said structure. 5 10

2. In metallic vapor current-rectifying apparatus, an anode, structure disposed about said anode for receiving the vapor particles and permitting of free flow of the same about and in contacting relation with said anode, and means disposed between said anode and said structure forming a free and unobstructed passage for flow of vapor particles thereinto after the same have passed beyond said anode, the said means providing a trap for condensate of the vapor formed therein and having a passage for discharging such condensate laterally outwardly from said anode exteriorly of said structure. 15 20

3. In metallic vapor current-rectifying apparatus, an anode, a structure disposed about said anode for receiving the vapor particles and permitting free flow of the same about and in contacting relation with said anode, said structure provided with a discharge opening permitting 30 free and unobstructed flow of said vapor therefrom after passage beyond said anode, and means for receiving said vapor comprising complementary members extending laterally outwardly from said opening and inwardly from said structure 35 and forming a tortuous path for conducting such vapor and any condensate thereof therethrough for discharge exteriorly of said structure.

4. In an electric power rectifier of the metallic fluid type having a metallic tank, anodes extending through apertures through the tank, means supporting said anodes and sealing the apertures, arc guides surrounding said anodes and formed to produce an upward flow of metallic fluid therethrough, said guides having a plurality of 40 45 apertures to form escape ports for fluid condensed therein, means for preventing the return of condensed fluid through the arc guides and having a portion thereof so formed as to cause condensed fluid to be discharged through said ports beyond 50 the outer surfaces of said guides.

OSKAR SEITZ.
